UNITED STATES PATENT OFFICE.

FELIX UNSÖLD, OF MUNICH, GERMANY, ASSIGNOR TO JOSEPH FISHBURN, OF WESTMINSTER, ENGLAND.

ICE-RINK.

SPECIFICATION forming part of Letters Patent No. 530,367, dated December 4, 1894.

Application filed May 12, 1894. Serial No. 511,018. (No model.)

To all whom it may concern:

Be it known that I, FELIX UNSÖLD, a subject of the Emperor of Germany, residing at Munich, Bavaria, Germany, have invented 5 new and useful Improvements in and Relating to Ice-Rinks, of which the following is a specification.

My invention relates to the construction of ice rinks for skating purposes.

10 In constructing and maintaining a sheet of ice for an ice rink it is necessary to abstract an amount of heat considerably in excess of that required to counteract the heat of the atmosphere in contact with the water or ice surface, this excess being due, among other causes, to the necessity for absorbing the heat conducted to the ice from the earth, by the floor or supports on which the sheet of ice is carried. Furthermore, the expansion and 15 contraction of this floor, or of these supports have frequently caused difficulty, and have resulted in their fracture, or in that of the sheet of ice.

Now the objects of my invention are to reduce the power necessary for the formation 20 and maintenance of the sheet of ice and of its surface by thoroughly insulating the floor from the earth; and to lessen the risk of fracture by providing for the ready expansion and 25 contraction of the floor and of the sheet of ice independently.

To enable my invention to be fully understood I will describe the same by reference to the accompanying drawings, in which—

30 Figure 1 is a plan of the floor for an ice rink constructed according to my invention; and Fig. 2 is a vertical section of the same. Figs. 3 and 4 are sectional views at right angles to each other showing the means for permitting 35 of the expansion and contraction of the floor, the said views being drawn to an enlarged scale. Figs. 5 and 6 are a plan and vertical section respectively showing the arrangement 40 of the pipes through which the freezing mixture is passed; and Figs. 7 and 8 are longitudinal and transverse sections respectively, illustrating the construction of an elastic joint which I advantageously use for the 45 said pipes.

50 *a* is the floor of the rink which is formed of boards (wood being a good non-conductor of

heat), the said boards being carried upon joists or girders *b* preferably of double channel or H-section (as shown most clearly in Fig. 4) supported upon piers or pillars *c*, *c*, 55 built up from the earth, thus constituting a chamber or chambers *d*, *d* beneath the said floor. Plates of wood *c'*, *c'* having upon them sheets *c²*, *c²* of felt, or similar elastic non-conducting material, are shown as being placed 60 on top of the piers or pillars and under the girders in order to assist in preventing heat from being conducted through the pillars to the girders and so to the floor.

The chamber or chambers is or are of such 65 depth that it or they can be used for storage of perishable goods or of ice, or for other similar purposes where a low temperature is required. The planks *e*, *e* of which my floor is composed are preferably formed of good 70 sound wood arranged so that the grain of the wood is lengthwise of the plank. These planks are laid with longitudinal spaces between them so as to permit of the independent 75 expansion of the said planks in the direction of their width, or across the grain of the wood.

To retain the planks *e*, *e* in position and yet permit of any movement of expansion or contraction, I fix them as follows, that is to say, 80 each plank is at one edge rigidly secured to the girders by bolts *f*, *f*, *f* while the other edge is fastened by means of clips *g*, *g* which are bolted to the planks and engage beneath the adjacent flanges of the girders, as shown 85 in Figs. 1 and 4. This construction allows each plank to expand and contract independently.

In order to retain the water before it is frozen upon the floor *a* it is necessary to fill 90 in the spaces between the planks *e*, *e* with some resilient material which will readily yield, such, for instance, as hemp or tow or pitch melted and run in while hot and to fix around the edges of the floor a curb *h* which, 95 with the floor, constitutes a basin for retaining the water to be frozen.

i, *i* are the pipes or tubes through which the freezing mixture is circulated, these being arranged over the floor *a*. The lengths of pipe 100 *i* are advantageously provided with flanges *j*, *j* at the ends which rest on the wood floor of

the rink, these flanges having packing-rings *k* of elastic material placed between them and being constructed so as to be clipped together, compressing the elastic material and thus forming the liquid-tight joints of the said pipes. Bolts *m*, *m* are provided to connect the flanges which are advantageously made flat upon one side as shown so as to lessen the thickness of the sheet of ice to be originally constructed and afterward maintained.

The pipes *i*, *i* are not continuous over the whole surface to be frozen, but are arranged in sections, being continuous, however, for each section. As shown in Fig. 5, each section is connected at one end to a main flow-pipe *n* and at the other end to a main return pipe *o*, these pipes being in communication with the machinery, or apparatus, for producing and maintaining the low temperature of the freezing mixture. The length of pipe in each section must be such that the freezing mixture returning to the main return pipe *o* after flowing through the length of the pipe in the section shall only have its temperature reduced by a few degrees, say, for instance, 5° Fahrenheit or even less below that of the mixture entering the section from the main flow pipe *n*; and I prefer that the inflow pipe of one section should be adjacent to the outflow pipe of the adjacent section as shown. The object of these arrangements is to insure as great a uniformity of temperature throughout the ice as possible; this being an advantage, not only for ease of maintenance of the sheet of ice, but for its formation originally. Furthermore, the construction of my rink floor gives a certain amount of elasticity to the sheet of ice, which renders a fall upon it

much less serious than a similar fall upon a sheet of ice supported only upon a rigid floor.

Having now particularly described and ascertained the nature of my said invention and in what manner the same is to be performed, I declare that what I claim is—

1. An ice rink having a chamber or chambers beneath the floor which may be used for storage purposes but which will insulate the ice from the earth and thereby prevent the conduction of the heat of the latter to the ice, the said floor being constructed of planks laid parallel with spaces between them and each rigidly secured to the supporting girders or joists at one edge only and loosely fastened thereto at the other edge so as to allow of expansion and contraction with variations of temperature, the spaces between the said planks being filled or caulked with hemp, tow or pitch, or other resilient material which will allow of the expansion and contraction of the planks all substantially as, and for the purposes, described.

2. The combination, in an ice skating rink floor, of joists, planks supported upon the said joists and laid with spaces between them, the said planks being rigidly secured at one edge only and a filling of resilient material in the said spaces substantially as, and for the purposes, described.

In testimony whereof I have hereunto subscribed my name in the presence of two witnesses.

FELIX UNSÖLD.
